PAGE 3

C. H. F.

*Fig. 4*Figure 1 is a side elevation of a toy battleship showing our new design, the other side being a mirror image thereof;

The dominant features of our design reside in the portions shown in full lines.

We claim:

The ornamental design for a toy battleship, as shown and described.
